Charles W. Waller, INVENTOR.

UNITED STATES PATENT OFFICE.

CHARLES W. WALLER, OF CHICAGO, ILLINOIS.

NECKTIE.

1,375,190.

Specification of Letters Patent. Patented Apr. 19, 1921.

Application filed February 21, 1919. Serial No. 278,330.

To all whom it may concern:

Be it known that I, CHARLES W. WALLER, a citizen of the United States, residing at Chicago, in the county of Cook and State of Illinois, have invented new and useful Improvements in Neckties, of which the following is a specification.

My invention relates to improvements in neckties, and the primary object of the invention is to provide a generally improved necktie having improved means whereby the use of a tie clasp will not wrinkle the tie, but instead cause the tie to retain its proper shape while a tie clasp is used, and also cause the tie to hang in a central straight vertical line instead of hanging to one side, as is the case when common ties are used in conjunction with tie clasps at one of the lateral edges of the tie.

20 A further object of the invention is to provide means to more easily tie or complete the tying of a four-in-hand necktie.

With the above mentioned and other ends in view, the invention consists in the novel construction, arrangement, and combination of parts, hereinafter described, illustrated in some of its embodiments in the accompanying drawings, and particularly pointed out in the appended claims.

30 Referring to the drawings forming a part of this specification,

Figure 1 is a front view in elevation of the principal form of the invention;

Fig. 2 is a front elevation of a modified form of the invention; and

Fig. 3 is a front elevation showing the finger invisible.

Similar numerals of reference designate like parts throughout all the figures of the drawings.

The present embodiment of the improved tie comprises an outer textile fabric flap face 1 and in order to prevent the tie from becoming wrinkled or forced to one side by 45 the use of a common tie clasp designated by 2, said outer flap portion is provided, preferably in its lower portion, with an aperture 3 which penetrates the face or entire thickness of said flap and permits the upper and 50 lower jaws of said tie clasp to engage the outer flap 1 of the tie and the underside of the button-hole band 4 of a shirt 5 respectively. If desired, the said aperture may be

elongated or made in the form of a slit, or, if desired, in addition to the small aperture 55 shown, an elongated aperture or slit 6 may be provided either above or below the aperture 3, said slit permitting the clasp 2 to be adjustably moved in said slit.

In order to keep the tie in proper position 60 relative to the shirt 5 the apertures 3 and 6 are in alinement with the edges of the band 4, preferably the edge 7 or right-hand edge.

If desired, the form shown in Fig. 1 may 65 be modified by the form shown in Fig. 2 in which one of the lateral portions of the outer face portion may be cut away, preferably the lower right lateral portion, as shown by 8 in Fig. 2, in which case a 70 straight vertical edge 9 is provided adjacent the medial vertical line of said tie, which is equivalent to the slit 6 in that it permits the clasp 2 to be adjustable along the edges 7 and 9, the upper portion of said 75 edge 9 being turned to one side, preferably to the right hand side of the wearer.

In the common types of four-in-hand ties it is very difficult to get a hold on the lower end of the outer flap 1 when attempting to 80 pull the same through the knot 10 while tying the same, and in order to facilitate this operation I provide, at the said lower end of the outer flap 1, a finger 11, which may be stiff, semi-stiff, or resilient, as de- 85 sired, and which pulls or pushes the lower end of the outer flap 1 through the knot 10 when said finger has been inserted at the top of and pulled through the bottom of the said knot by the fingers of the wearer. 90

The said finger may be secured to the tie in any suitable manner such as, for instance, sewing 12, and said finger may be made to extend downwardly a suitable distance as shown in Fig. 1, or may, if desired, be in- 95 visibly secured to the back of said outer flap as shown in Fig. 3.

While I have shown in the drawings the tie already tied, the finger 11 is intended for use only in connection with the four-in-hand type of tie, while I wish it understood that the aperture 3, slit 6, and the cut away lateral portion 8 may be employed in either the four-in-hand or ready-made types of ties. 100

105 From the foregoing description, taken in

connection with the accompanying drawings, the construction and advantages of my invention will be readily understood.

Having thus described an embodiment of my invention, what I claim and desire to secure by Letters Patent is,—

- 5 1. In a four-in-hand fabric necktie, its outer flap having the back side of its lower portion provided with a finger.
- 10 2. A four-in-hand necktie having its outer flap provided with an aperture which pene-

trates the face of said outer flap, and said aperture adapted to receive the jaw of a tie clasp.

3. A four-in-hand fabric necktie comprising an outer flap provided with an aperture which penetrates the face of said outer flap, said aperture adapted to receive the jaw of a tie clasp, and the extreme lower portion of said outer flap provided with a finger.

CHARLES W. WALLER.
